UNITED STATES PATENT OFFICE.

OTTO W. RINGQVIST, OF FITCHBURG, MASSACHUSETTS, ASSIGNOR, BY MESNE ASSIGNMENTS,
TO MARY ELIZABETH JOHNSON, TRUSTEE, OF FITCHBURG, MASSACHUSETTS.

HINGE-PIN FOR BREAKDOWN GUNS.

No. 893,014.

Specification of Letters Patent.

Patented July 14, 1908.

Application filed July 8, 1902. Serial No. 114,739.

To all whom it may concern:

Be it known that I, OTTO W. RINGQVIST, a citizen of the United States, residing at Fitchburg, in the county of Worcester and 5 Commonwealth of Massachusetts, have invented a new and useful Improvement in Hinge-Pins for Breakdown Guns, of which the following is a specification, accompanied by drawings forming a part of the same, in 10 which—

Figure 1 is a side view of a portion of a break down gun, showing my improved hinge pin. Fig. 2 is a top view of the same. Fig. 3 is a section on line 3—3, Fig. 1, looking 15 toward the rear of the gun. Figs. 4 and 5 are perspective views of my improved hinge pin. Fig. 6 is a side view of my improved hinge pin shown partly in section. Fig. 7 is a side view of the same showing the hinge pin applied to 20 the frame of the gun, and Fig. 8 is an enlarged diagrammatic view showing the eccentricity of the joint between the frame and the forestock. The ends of the handle D are knurled at K and L.

Similar reference letters and figures refer to 25 similar parts in the different views.

My invention relates to improvements in hinge pins for break down guns and is designed to furnish means for the easy insertion and withdrawal of the hinge pin, and also 30 to prevent the removal of the hinge pin except when the gun is broken down, and it consists in the construction and arrangement of parts as hereinafter described and pointed out in the annexed claims.

Referring to the accompanying drawings A denotes the gun stock with the frame A¹ attached thereto. The barrel B is pivotally attached to the frame A¹ by the hinge pin C which passes through the holes D³, D³, in the 40 frame A¹ and the hole B¹ in the rib B² of the gun barrel B; said gun barrel B turning on said hinge pin C when the gun is broken down. The hinge pin C is screw threaded at one end C¹ and is adapted to screw into corresponding screw threads in one of the holes D³ in the frame A¹ of the gun. At the opposite 45 end of the hinge pin C is a bifurcated head C² which is held in the recess C³ on the opposite side of the frame from the screw threaded hole D³. The handle D of the hinge pin C is adapted to enter the bifurcation in the head C² and is provided with a slot D⁴ through 50 which a pivot pin E, held in the head C² extends, whereby the handle D has a pivotal connection with the hinge pin C and is also

adapted to receive a sliding motion in the bifurcated head C². A tail piece D² at one end of the handle D is formed to abut against the hinge pin C and limit the outward rotation of the handle C on the pivot pin E, Figs. 4 and 60 6. A locking pin F and spring G are provided in the hinge pin C and the locking pin F bears against the handle D opposite the pivot pin E. When the hinge pin C is in its proper position in the gun, the handle D is 65 depressed into a recess I in which it is held by the locking pin F, Figs. 5 and 7. When the handle D is in its elevated position the pin F bears against the shoulder J and retains the pin F in that position. The ends of the handle D are knurled at K and L.

Fig. 8 is a diagrammatic view which is designed simply to show the action of the eccentric joint between the ends of the frame A¹ and the forestock x which is attached to 75 the barrel in the ordinary manner. The solid line F¹ in Fig. 8 shows the actual joint as governed by the convex ends of the frame A¹. The concave plane of the ends of the forestock x attached to the barrel would 80 normally follow the line F² as the barrel is rotated on the hinge pin and the gun is closed, but the eccentric construction of the convex ends of the frame A¹ forces forward the forestock x and with it the barrel and 85 rib B² a distance equal to the difference between the solid line F¹ and the broken line F² which is also the difference between the centers O and P of circles corresponding to lines F¹ and F². This brings the hole B¹ in 90 the rib of the barrel slightly out of alignment with the holes D³, D³, in the frame and hence the hinge pin is held firmly in its position. When the gun is broken down the broken line F², showing the normal position of the 95 concave end of the forestock, rotates entirely below and forward of the line F¹, which is the position of the concave ends of the frame A¹, so that instead of binding there is a slight longitudinal play between 100 the frame and the forestock x. When the gun is broken down, therefore, the hinge pin C may be readily unscrewed, but when the barrel is in the position shown in Fig. 1, the slight binding action upon the hinge pin C 105 prevents its removal, thereby locking the hinge pin.

The method of operation of my improved hinge pin is as follows:—When the gun barrel is placed in the broken down position, the 110

hinge pin C is inserted in place and screwed in by means of the handle D which is placed in the position shown in Figs. 4 and 6 to serve as a lever handle for the hinge pin.

- 5 When completely inserted the bifurcation in the head C² is in alinement with the recess I and pressure upon the knurled end K depresses the handle D to a position approximately at right angles with the hinge pin C, 70
 10 and into the recess I, as shown in Figs. 5 and 7. The barrel is then closed in the position shown in Fig. 1, and the eccentricity of the joint F¹ moves the hole B¹ in the rib B² of the barrel, which slightly binds the hinge pin C and locks it in position. In taking the gun 75
 15 apart, it is first broken down to prevent the binding of the hinge pin, the handle D is then swung into its outward position, as shown in Figs. 4 and 6, by pressure upon the knurled 80
 20 end L and the hinge pin C unscrewed by means of the handle D.

What I claim as my invention and desire to secure by Letters Patent is:—

1. In a break down gun, a screw threaded 25 hinge pin provided with a pivot pin in one end, a lever handle provided with a slot inclosing said pivot pin, whereby said handle is capable of both a rocking and a sliding motion on its pivotal connection, and means 30 for limiting the outward swing of the lever handle.

2. In a break down gun, the combination with a frame and barrel hinged thereto, of a screw threaded hinge pin provided with a pivot pin at one end, a lever handle provided with a slot inclosing said pivot pin, whereby said lever handle is capable of both a rocking and sliding motion on its pivotal connection, means for applying a yielding pressure to 35 said lever handle and means for limiting the outward swing of said lever handle, substantially as described.

3. In a break down gun, the combination with a frame having a hole therein to receive 45 a hinge pin and provided at its outer surface with a recess extending diametrically across said hole, of a screw threaded hinge pin held in the frame, a lever handle having a pivotal connection with one end of said hinge pin 50 and adapted to lie in its normal position in said recess, whereby the handle is locked against turning, said handle having a slot inclosing the pivot, whereby it is capable of both a sliding and rocking motion on its 55 pivotal connection with said hinge pin and means for limiting the outward swing of said lever handle, substantially as described.

4. The combination with the frame of a break down gun, having a hole therein to 60 receive a hinge pin and provided on its outer surface with a recess diametrically across said hole, of a hinge pin adapted to enter the hole in the frame, a slotted handle having a pivotal connection with said hinge pin and 65 capable of both rocking and sliding on said

pivotal connection, means for applying a yielding pressure to said slotted handle, and means for limiting the outward swing of said handle, substantially as described.

5. A hinge-pin for break-down guns comprising a pin proper having a screw thread at one end and a bifurcated head at the other, a handle provided with a slot located at or near one end thereof, and extending substantially parallel with the edges of the handle, the handle fitted in the bifurcated head and retained therein by a pin which passes through the slot, and a spring actuated pin fitted to a bore formed in the hinge-pin proper, and bearing at all times upon some portion of the handle immediately opposite the pivot pin. 70
 75

6. A hinge-pin comprising a pin proper threaded at one end and provided with a bifurcated head at the opposite end, a handle having a slot and sliding pivotal connection in the bifurcated portion of the head, said handle provided with a tail-piece and shoulder adjacent thereto, and a spring actuated locking pin which has a sliding connection in 80 the bore formed in the axial center of the pin proper, and bearing outwardly at all times upon some portion of the handle adjacent to the inner edge of the elongated slot, whereby to retain the handle yieldingly in position. 85
 90

7. The combination with the frame of a break-down gun having a hole therein for the reception of a hinge pin and provided with an elongated recess in its outer surface which extends parallel or approximately parallel 100 with the length of the frame and crosses the hole for the hinge-pin, of a hinge pin adapted to be inserted in the hole, and provided with a bifurcated or slotted head which alines with and forms a continuation of the recess 105 when the hinge pin is inserted in the hole to its fullest extent, and a handle having sliding pivotal connection within the slotted or bifurcated portion of the head, and adapted when the screw is in its normal position to be 110 swung into the recess in the frame of the gun whereby to lock the hinge-pin against turning.

8. The combination with the frame of a break down gun, of a barrel provided with a rib, holes in said frame and in said rib, a 115 hinge pin inserted in said holes, and means for moving the hole in said rib out of alinement with the holes in the frame when the barrel is swung into the firing position.

9. The combination with the frame of a 120 break down gun, of a barrel provided with a rib, holes in said frame and a single hole in said rib, and means for moving said rib laterally when the barrel passes from its break down to its firing position.

10. The combination with the frame of a break down gun, of a barrel provided with a rib, holes in said frame and a single hole in said rib, said holes being concentric when 125 said barrel is broken down, and a joint be- 130

tween said rib and said frame which is slightly eccentric to said holes in the frame.

11. The combination with the frame of a break down gun, of a barrel provided with a rib, holes in said frame and in said rib, a hinge pin inserted in said holes, a forestock attached to said barrel, an eccentric joint between said frame and said forestock, whereby the holes in said rib and the hole in said barrel are brought slightly out of alinement when said barrel is in the firing position.

12. The combination with the frame of a

break down gun, of a barrel provided with a rib, a hinge pin connecting said rib and said frame, and means operated by the movement of the barrel on the hinge pin for binding the hinge pin when the barrel is in the firing position.

15

Dated this 27th day of June 1902.
